INVENTOR:

Thomas Edward Batty
By Wm Wallace White
ATTY.

UNITED STATES PATENT OFFICE.

THOMAS EDWARD BATTY, OF SHEFFIELD, ENGLAND.

CONVEYER AND THE LIKE.

1,413,956.

Specification of Letters Patent. Patented Apr. 25, 1922.

Application filed January 13, 1921. Serial No. 437,016.

To all whom it may concern:

Be it known that I, THOMAS EDWARD BATTY, of Woodseats, Sheffield, England, a subject of the King of Great Britain and Ireland, have invented certain new and useful Improvements in or Relating to Conveyers and the like, for which I have obtained Letters Patent in Great Britain #122,013, filed January 8, 1918, and of which the following is a specification.

This invention relates to conveyers and especially to conveyers adapted to carry carbonaceous material through apparatus employed in the production of smokeless fuel and recovery of by-products.

In a conveyer made in accordance with this invention I provide an endless chain comprising four parallel sets of links, each outer set of links being connected to an inner set by common pivot pins; distance pieces and rollers alternately disposed on the pivot pins; two cross bars disposed with a space between them on each opposite pair of the inner links; and plates mounted on the cross bars forming half the enclosing walls of two receptacles for the carbonaceous material, said receptacles having two of their inner walls sloping so that they overhang the spaces between the cross bars and may be thoroughly heated.

Referring to the drawings filed with the specification:—

Fig. 1 is a part sectional elevation of one form of conveyer made in accordance with this invention;

Fig. 2 is a part sectional plan;

a a are links pivoted together by means of pivot pins b b; between the links a a are distance pieces c c and rollers d d alternately disposed on said pins. The links and rollers form a chain. On the inner links are mounted trough shaped brackets e e; supported between two chains formed as above described and mounted on brackets e e are cross bars f f. On the cross bars f f are plates g g' flanged at the bottom as at h and at the sides as at j. The bottom and side flanges of one plate overlap the bottom and

side flanges of an adjacent plate. The plates g on one link and g' on an adjacent link and flanges form the enclosing walls of a receptacle adapted to receive the carbonaceous material; the adjacent walls of successive receptacles converging or sloping towards each other at the upper ends thereof so as to overhang the spaces between the cross bars f and form between the receptacles a space m exposed to the heat of the furnace. In place of the distance pieces c c, rollers such as d may be employed.

In use, the material is placed in the receptacle and passed through the apparatus. The material becomes distilled or coked in the process. On arriving at the end of the apparatus, the conveyer chain passes over a polygonal or circular drum causing the trough-like receptacles to open and discharge the material, the bottom flanges tending to break up and discharge the material.

With a conveyer made in accordance with this invention the material is readily discharged and the use of prongs, rakes and bars is not necessary.

What I claim and desire to secure by Letters Patent is:—

In a conveyer adapted to carry carbonaceous material through apparatus employed in the production of smokeless fuel and recovery of by-products, an endless chain comprising four parallel sets of links, each outer set of links being connected to an inner set by common pivot pins, distance pieces and rollers alternately disposed on the pivot pins, two cross bars disposed with a space between them on each opposite pair of the inner links, and plates mounted on the cross bars forming half the enclosing walls of two receptacles for the carbonaceous material, said receptacles having two of their inner walls sloping so that they overhang the spaces between the cross bars and may be thoroughly heated.

In testimony whereof I have signed my name to this specification.

THOMAS EDWARD BATTY.
